CHIN REST

Filed March 2, 1928

Inventor
CHARLES L. PAULUS

By Robert H. Young, Atty.

UNITED STATES PATENT OFFICE

CHARLES L. PAULUS, OF DAYTON, OHIO

CHIN REST

Application filed March 2, 1928. Serial No. 258,584.

This invention relates to machine guns, more particularly to rests for aiding the sighting of fixed airplane machine guns, and has for an object to provide a chin rest which will support the head of the gunner in a dive or other violent maneuver and enable him to keep his eye in proper alignment with the gun sights.

A further object is to provide a chin rest for the fixed machine gun of an airplane which may be interchangeably mounted in the sight sockets of the airplane.

A further object is to provide a chin rest of the kind described which may be easily and quickly adjusted to engage the chin or side of the face of the gunner and permit the use of either eye in sighting the gun.

With the above and other objects in view the invention consists of certain novel details of construction and combination of parts hereinafter fully described and claimed, it being understood that various modifications may be resorted to within the scope of the appended claims without departing from the spirit of the invention.

In the accompanying drawing in which like numerals of reference designate the same parts throughout—

Figure 1 is a top plan view of a chin rest constructed in accordance with my invention;

Figure 2 is a side elevation of the chin rest;

Figure 3 is a fragmentary sectional view on the line 3—3 of Figure 2;

Figure 4 is a diagrammatic view of the chin rest in operation.

Nearly all the late types of military aircraft are equipped with three sets of fixed gun sight sockets disposed along the longitudinal axis of the airplane, one set being located in the center as shown at 1 and one set on either side of the center as shown at 2 and 3. This arrangement of sockets permits the gunner to mount the sight 4 either in the center of the cowl or on either side of the cowl by engaging the mounting pins 5 of the sight in the corresponding sight sockets. The present invention provides a chin rest which may be mounted in either set of the sight sockets not being used for the sight.

The chin rest comprises a tubular support 6 which is closed at one end by a cap 7 and is bent laterally near the opposite end and terminates in a split ring clamp 8 which receives the chin rest frame. The frame comprises spaced bifurcated plates 9 connected together at the forward ends by a tubular rod 10, which is mounted to turn within the clamp 8, and is locked against twining by a bolt 11. The free ends of the plates are connected together by spacing bolts 12. A pair of similar pads 13 are disposed at an angle to each other between the plates to receive the chin of the gunner. Each pad is preferably formed of sponge rubber and is reinforced internally to retain its shape by a rigid metal core 14 which terminates in eaves 15 which receive the spacing bolts.

A pair of mounting pins 16 are provided for securing the support 6 to the sight brackets, each pin terminating in a split ring clamp 17 which receives the tubular support and may be locked in any adjusted position thereon by a bolt 18. These pins are adapted to be interchangeably received in the openings of any set of the sight brackets and are secured in position by nuts 17.

To facilitate easy adjustment and removal of the chin rest frame the terminals of the split ring clamp are hinged as shown at 20 to the body of the clamp.

In operation, the tubular support 6 may be slid longitudinally through the clamps 17 of the mounting pins to position the pads 13 of the chin rest against the chin of the gunner. The support may also be rotated on its axis in the clamps for securing the mounting pins in either set of idle sight brackets. Also the frame of the chin rest may be swung laterally on the end of the support 6 by loosening the bolt 11 to position the pads against the chin or side of the face of the gunner and also to permit either eye being used for sighting.

Having thus described my invention what I claim is—

1. A chin rest for sighting machine guns, comprising a support adjustable about its longitudinal axis, a frame mounted on said support and adjustable about an axis at right angles to the longitudinal axis of the support, a pair of spaced bifurcated plates connected together at their forward ends by a tubular rod, the plates being disposed at an angle to each other, a pair of pads disposed between the plates to receive the chin of the gunner, each pad being formed of a soft material and reinforced internally by a rigid metal core, a split ring clamp secured to the rear end of the support, the clamp receiving the frame, the plates being secured to the support by a pair of mounting pins, each pin terminating in a split ring clamp which receives the support, the pins being received in the openings of the sight brackets, the split ring clamp being hinged to the body of the clamp.

angles to said support and a pad on said frame adapted to receive the chin of the gunner.

2. A chin rest for sighting machine guns, comprising a laterally and longitudinally adjustable support, a frame connected to said support and adjustable about an axis at right angles thereto and a pad secured to said frame to receive the chin of the gunner.

10 3. A chin rest for sighting machine guns, comprising a laterally and longitudinally adjustable support, a frame connected to said support and adjustable about an axis at right angles thereto and a plurality of pads arranged in the form of a V secured to said frame to receive the chin of the gunner.

4. In combination with an airplane provided with a plurality of sight sockets spaced laterally with respect the longitudinal axis 20 of said airplane, of a chin rest support adapted to be interchangeably secured to said sight sockets comprising a laterally and longitudinally adjustable support, a frame pivotally and adjustably connected to one end of said support and a pad secured to said frame to receive the chin of gunner.

In testimony whereof I affix my signature.
CHARLES L. PAULUS.
